UNITED STATES PATENT OFFICE.

ELIZABETH O'BRIEN AND MARIE G. VIERLING, OF MINNEAPOLIS, MINNESOTA,
ASSIGNORS TO LOUIS F. DOW CO., OF ST. PAUL, MINNESOTA, A CORPORA-
TION.

PENCIL.

Application filed April 6, 1921. Serial No. 458,954.

To all whom it may concern:

Be it known that we, ELIZABETH O'BRIEN and MARIE G. VIERLING, citizens of the United States, residing at Minneapolis, in 5 the county of Hennepin and State of Minnesota, have invented certain new and useful Improvements in Pencils; and we do hereby declare the following to be a full, clear, and exact description of the invention, 10 such as will enable others skilled in the art to which it appertains to make and use the same.

Our invention has for its object to provide an extremely simple and highly efficient lead 15 pencil, and to this end, it consists of the novel devices and combinations of devices hereinafter described and defined in the claims.

In the accompanying drawings, which 20 illustrate the invention, like characters indicate like parts throughout the several views.

Referring to the drawings:

Fig. 1 is an elevation of the improved 25 lead pencil;

Fig. 2 is a view principally in longitudinal central section, on an enlarged scale;

Fig. 3 is a fragmentary view of the inner 30 end of the inner casing removed from the outer casing; and

Fig. 4 is a detail view of the lead-holding stem removed from the inner casing, with some parts sectioned.

The numerals 5 and 6, respectively, indicate 35 inner and outer casings telescopically connected with freedom for compound axial and rotary movements in respect to each other. The outer casing 6 has a contracted or pointed end 7, through the nose of which 40 lead may be fed or retracted, as will presently appear. The outer end of the inner casing 5 is circumferentially expanded to afford a holder 8 for an eraser 9, and which holder is provided with an inwardly pressed annular 45 bead 10, against which is stopped the eraser.

A stop shoulder 11 is afforded by the inner 50 end of the holder 8 for engagement with the outer casing 6 to limit the axial movement of the inner casing into the outer casing.

On the inner end of the inner casing 5 is a lead-holding stem comprising a pin 12 having a head 13, preferably with curved upper and lower surfaces, and around which 55 stem is folded a sleeve 14 that terminates

short of the head 13, at one end, and its 55 other end is extended beyond said pin and provided with a pair of spring jaws 15 adapted to receive and yieldingly hold one end of a lead 16. The other end of the lead 16 is loosely held and guided in the nose of 60 the casing point 7. The end of the pin 12 affords a stop for holding the lead 16 against inward endwise movement during writing action.

The lead-holding stem is secured to the 65 inner casing 5 with freedom for wobble movement by inserting the same through a washer 17 in the inner end of the inner casing 5 before the sleeve 14 is secured thereto. To afford a thrust bearing for the lead-holding 70 stem, there is placed in the inner casing 5 a disk 18 against which the head 13 bears and which thrust bearing also holds said head onto the washer 17. Both the washer 17 and thrust bearing 18 are held in position by pressing the inner casing 5 inward to afford annular beads 19.

The ends of the inner casing 5 are closed by the eraser 9 and thrust bearing 18 and afford a cell in which spare leads may be 80 kept and which cell is provided with a longitudinal slot or passageway 20 normally closed by the outer casing 6. Obviously, by drawing the inner casing 5 out of the outer casing 6 to expose the passageway 20, leads 85 may be inserted into the cell or removed therefrom. By holding the outer casing 6 and turning the inner casing 5 by taking hold of the eraser holder 8, which affords a good finger hold, said inner casing may 90 be rotated in the outer casing and, at the same time, moved endwise to feed the lead 16 through the point 7. The frictional engagement between the two casings will hold the inner casing wherever set. To increase 95 the frictional engagement between the two casings, the inner casing may be circumferentially expanded, as indicated at 21 in Fig. 3.

The thrust bearing 18 securely holds the 100 lead holder against endwise movement during writing action and, at the same time, the lead 16 is held against inward endwise movement by its engagement with the end of the pin 12. The nose of the point 7 is of such 105 size as to permit the lead 16 to freely move therethrough without any friction whatsoever and the wobble movement of the lead

holder will keep said lead holder and the lead in alignment, so as to relieve any bending of the lead, which would break the same.

The above described invention, while extremely simple and of small cost to manufacture, has, in actual usage, proven highly efficient for the purpose had in view. By frictionally holding the casings with the lead holder in different adjustments, it is possible to dispense with lead-feeding mechanism and lead-guiding mechanism used in commercial pencils.

A separate application having been filed covering the features of construction by 15 which the frictional engagement between the casings is secured, said features are not claimed in this application.

What we claim is:

1. A pencil comprising inner and outer 20 telescopically connected casings, a lead-holder, and a washer supported in the inner end of said inner casing, said washer supporting said lead holder with freedom for wobble movement of said lead holder.
2. A pencil comprising inner and outer 25 telescopically connected casings, the former of which has a washer-like inner end, a lead-feeding stem extending through said washer-like end and having a head held between 30 said washer-like end, and a thrust bearing in the inner casing, said inner casing being free for axial movement in the outer casing to feed a lead through the contracted end thereof or retract the same.
3. A pencil comprising inner and outer 35 telescopically connected casings, the former of which has a washer-like inner end, a lead-feeding stem extending through said washer-like end and having a head held between said

washer-like end and a thrust bearing in the 40 inner casing, said washer-like end and thrust bearing holding the lead-feeding stem with freedom for wobble movement, said inner casing being free for axial movement in the outer casing to feed a lead through the contracted end thereof or retract the same. 45

4. A pencil comprising inner and outer 50 telescoping casings, the former of which has a washer-like inner end, a stem supported in said washer-like end and projecting toward the outer end of the outer telescoping member, and a sleeve surrounding said stem and projecting beyond the outer end thereof, the projecting end of said sleeve being formed with spring lead-holding jaws. 55

5. A pencil comprising inner and outer 60 telescoping casings, the latter of which has a contracted lead opening at its outer end and the former of which has a doubled-wall inner end, a stem formed with a head secured between said outer end walls of the inner casing, said stem projecting toward the outer end of the outer casing, and a sleeve surrounding said stem and formed with a lead-holding portion extending beyond said 65 stem.

6. A pencil comprising inner and outer 70 telescoping casings, a stem centrally supported in the inner end of the inner casing and projecting toward the outer end of the outer casing, and a sleeve surrounding said stem and projecting beyond the same, the projecting portion of said sleeve forming a lead holder.

In testimony whereof we affix our signatures. 75

ELIZABETH O'BRIEN.
MARIE G. VIERLING.
